UNITED STATES PATENT OFFICE.

SHERMAN MONCRIEF, OF CENTER JUNCTION, IOWA.

BROOM-HOLDER.

1,275,070.

Specification of Letters Patent.

Patented Aug. 6, 1918.

Application filed April 19, 1917. Serial No. 163,294.

To all whom it may concern:

Be it known that I, SHERMAN MONCRIEF, a citizen of the United States, residing at Center Junction, in the county of Jones and 5 State of Iowa, have invented certain useful Improvements in Broom-Holders, of which the following is a specification, reference being had therein to the accompanying drawing.

10 This invention has reference generally to improvements in that class of inventions known as buckles, buttons and clasps and more particularly relates to a spring holder for the handles of brooms, tools and other 15 objects or articles capable of being suspended by their handles.

As the primary aim and object the present invention resides in the provision of novel means formed on the body of the holder and 20 partly about the opposed resilient coils for coöperating with a fastening device in effectively anchoring the holder in position and for causing the resilient coils to move outwardly and at approximately right angles 25 to the body when a handle is inserted between the coils for spreading them, consequently insuring an effective engagement of the coils with handles of various diameters.

30 Among the other aims and objects of the present invention may be recited the provision of a device of the character described with a view to compactness, and in which the number of parts are few, the construction simple, the cost of production low and the efficiency high.

Other objects as well as the nature, characteristic features and scope of this invention will be more readily apparent from the 40 following description taken in connection with the accompanying drawings and pointed out in the claims, forming a part of this specification.

The preferred embodiment of the present 45 invention is clearly illustrated in the accompanying drawings, in which:—

Figure 1 is a perspective showing a broom handle supported therein.

Fig. 2 is a perspective looking toward the 50 rear surface of the device.

Fig. 3 is a transverse section taken through the device when it is attached to a support, and

Fig. 4 is a longitudinal section of the invention.

Similar characters of reference are em-

ployed in all of the above described views, to indicate corresponding parts.

Referring now, more particularly, to the accompanying drawings there is provided 60 a holder formed from a single strip of resilient metal including a body 1, the respective ends of which are coiled inwardly upon themselves to provide opposed and spaced resilient handle engaging coils 2. The body 65 is also provided centrally thereof and intermediate the coils with a fastening device receiving opening 3.

With a view toward providing the improved means for facilitating the anchoring 70 of the holder and for causing the coils to move outwardly when a handle is inserted therebetween, spaced longitudinally extending ribs 4 are formed on the rear surface of the body adjacent the marginal edges, said 75 ribs also extending partially about the outer surface of the coils 2 and terminating at points approximately one-eighth of the distance around the coils so that when a broom handle 5 or the like is inserted between the 80 coils they will be caused to move outwardly from the body and at right angles thereto while they are being spread by the broom handle. As indicated in the drawings the ribs are preferably provided by bending the 85 marginal edges of the resilient strip. By the arrangement of the ribs it will be appreciated that the coils are now capable of effectively receiving and supporting in a suspended position various sized handles of 90 brooms and similar articles.

Coöperating with the ribs is a fastening device which may be and preferably is a screw 6 said screw being insertible through the opening 3 and engageable with a suitable support 7 so as to clamp the ribs into biting engagement with the said support, consequently enabling them to coöperate with the single fastening device in preventing accidental movement of the holder, thus 100 insuring an effective securing of the holder in position.

In view of the foregoing description it is thought that a detailed description of the operation of the invention is entirely unnecessary. Likewise it is believed that the advantages of the invention are readily apparent.

It will be understood that the foregoing description and accompanying drawings 110 comprehend only the general and preferred embodiment of this invention and that vari-

ous minor changes in detail of construction, proportion and arrangement of the parts may be made within the scope of the appended claims and without sacrificing any of the 5 advantages of this invention.

Having thus fully described this invention, what is claimed is:

1. A broom holder formed from a single strip of resilient metal including a body, opposed handle engaging coils formed on the respective extremities of the body, spaced longitudinally extending ribs formed on the rear surface of the body adjacent the marginal edges thereof and also formed on and 10 extending partially about the outer surfaces of the coils and terminating at points approximately one-eighth of the distance around the coils whereby to cause the coils to move outwardly from the body when a 15 handle is inserted between the coils so as to spread them.
2. A broom holder including a body

formed from a single strip of resilient metal and having a central opening therein, spaced handle engaging coils formed integral with the respective ends of the body, spaced longitudinally extending ribs formed integral with the rear surface of the body adjacent the marginal edges thereof and also formed integral with and extending partially about 30 the outer surfaces of the coils and terminating at points approximately one-eighth of the distance around the coils, whereby when a handle is inserted between the coils to spread them the coils will be moved outwardly from the body and at substantially right angles thereto, and a fastening device engageable with the opening and with a suitable support for forcing the ribs on the body into biting engagement with a support 35 and coöperating with the ribs for anchoring the holder in a substantially rigid position.

In testimony whereof I affix my signature.

SHERMAN MONCRIEF.
